UNITED STATES PATENT OFFICE

2,435,536

WRINGER

Donald K. Ferris, Dayton, Ohio, assignor to General Motors Corporation, Dayton, Ohio, a corporation of Delaware

Application November 11, 1943, Serial No. 509,828

8 Claims. (Cl. 68—255)

1

This invention relates to wringers such as are used in connection with washing machines.

Many different forms of controls have been provided for wringers. I believe that four forms are most desirable. The first two of the most desirable forms of controls are the clutch control and the swing lock release which are almost universally provided. A third desirable control is an interlock between the swing lock release and the clutch control; there has been little commercial use of this device. A fourth control is what is called an instinctive release wherein a sufficiently violent pull or push on the wringer or tug upon the clothes is sufficient to stop the wringer. There has been little or no commercial use of this safety feature. This is a valuable safety feature since almost any forceful instinctive movement by anyone who might happen to have his hand or clothing caught in the wringer is sufficient to operate the instinctive release mechanism to stop the wringer.

It is an object of my invention to embody all these features in a wringer in such a simple way that it can be provided in low price wringers and yet be so satisfactory and efficient that it will be superior to those controls which may be found in high price wringers.

It is another object of my invention to provide a single, simple, inexpensive control member which performs several functions previously performed by a number of separate control members.

It is another object of my invention to provide a single member which performs the instinctive roll stop release and acts as a releasable swing lock as well as an interlock release.

It is another object of my invention to provide a simple means whereby the instinctive release is compensated for the torque reaction of the wringer.

It is another object of my invention to provide means for stopping the wringer when the load is excessive in either direction of operation.

It is another object of my invention to arrange the instinctive release in such a way that it will also function as an overload release.

It is another object of my invention to provide an improved clutch operating mechanism which will operate more easily and be simple and inexpensive.

It is another object of my invention to provide an improved clutch positioning means which will have little wear.

These objects are attained by providing a clutch operating cam member operated by either a longitudinal movement or a pivoted movement in

2

either direction of a floating lever connecting the wringer with the wringer support. The lever is moved longitudinally to release it from a slotted connection with the wringer support to provide

5 a swing lock release and to cam the clutch operating member to the neutral position. The lever is pivoted by the movement of the wringer relative to the wringer support in either direction to cam the clutch operating member to the neutral position. To compensate for the drive shaft torque acting on the wringer, the spring opposing the free movement of the lever has a greater tension in the direction resisting the torque of the drive shaft than in the opposite direction.

10 Further objects and advantages of the present invention will be apparent from the following description, reference being had to the accompanying drawings, wherein a preferred form of the present invention is clearly shown.

20 In the drawings:

Fig. 1 is a sectional view through a wringer head and wringer support showing one form of my invention;

Fig. 2 is a sectional view taken on line 2—2 of Fig. 1;

Fig. 3 is a sectional view taken along the line 3—3 of Fig. 1; and

Fig. 4 is a view in elevation of the spring shown in Figs. 1 and 2.

30 Referring now to the drawings, there is shown a wringer head 20 having a downwardly extending cylindrical portion 22 which is rotatably mounted upon a vertical post 24. This post is provided with a flange 26 which may be made in one or two pieces pressed onto the post 24 and locked thereon by some suitable means such as a set-screw. The post 24 is hollow and contains a hollow drive shaft 28 extending upwardly from the power element of the washing machine. This

35 hollow drive shaft 28 is provided with diametrically opposite slots 30 at its upper end which receive the driving pin 32 of the splined clutch shaft 34. This splined clutch shaft 34 is supported by upper and lower bearings 36 and 38 in

40 the wringer head 20. The clutch shaft 34 is prevented from moving axially by a shoulder provided on the shaft 34 beneath the gear 42 and by a washer 37 which is held in place by a nut 39 threaded onto the end of the clutch shaft 34.

45 The clutch shaft 34 is provided with a slidable jaw clutch member 40 which is splined to slidably fit the splines in the clutch shaft 34.

This slidable clutch member 40 has recesses and teeth at its upper and lower ends for engagement with complementary recesses and

teeth provided upon the adjacent ends of the upper and lower bevel gears 42 and 44 rotatably mounted upon the clutch shaft 34. These gears are constantly enmeshed with a bevel crown gear 46 connected by the shaft coupling 48 to the drive roller 50 of the wringer which is in engagement with the idler pressure roller 52 in the usual manner. The remainder of the wringer is not shown since it is conventional and its construction may be like that shown in the Kauffman Patent 2,266,498.

The slideable clutch member 40 is held in its middle or neutral position shown in Fig. 1, or in its upper or lower position in engagement with either the upper or lower bevel gears 42 or 44, by a roller 54 which rides in a groove 56 extending around the midpoint of the member 40. This roller is rotatably mounted by means of a screw 58 and a spacer member threaded into a triangular shaped lever 60 pivoted by a pin 62 to the adjacent wall of the wringer head.

This lever 60 at its opposite end is provided with a middle notch 64 and upper and lower notches 66 and 68. A roller 70 is provided upon the end of a quarter elliptic spring member 72 which is fastened to the wringer head. The engagement of the roller 70 with either of the notches serves to yieldingly retain the clutch member 40 in any one of its three positions. The lever 60 is moved from any one of the positions to any of the other positions by an eccentrically located pin 74 which extends into a slot 76 provided in the lever 60 adjacent the notch 64. This pin is provided in the inner face of a cam member 78 which is rotatably mounted in a bearing 80 provided with a transverse pin 82 for preventing axial movement. This cam member 78 is connected to an operating shaft 83 supported by a strap member 84 and provided with an operating handle 86 at its outer end.

Heretofore it has been the practice to provide the roller directly upon the cam member and this has resulted in the roller being considerably off the exact radial position in the groove of the clutch operating member. This has resulted in considerable binding, wear and difficult operation. Also it has been customary to provide the spring latching mechanism directly on the cam member. Because of the small amount of movement of the cam member and the small area of contact which it could provide for latching, this arrangement was subject to considerable wear and it failed to hold the clutch member in proper position when worn. By providing the lever 60 in between the cam member 78 and the clutch member 40 I provide a much greater surface and a much greater leverage for the spring latch mechanism, particularly since it is possible to use a roller with the notches 64 to 68. The roller 54 is sufficiently far from the pivot pin 62 that in the amount of movement required of the lever 60 in either direction from its neutral position the roller 54 does not move any substantial distance off the line of the true radial position.

The rotatable mounting of the wringer head 20 upon the wringer support which includes the post 24 and the flange 26 makes it possible to swing the wringer around to a number of positions. In order to latch the wringer, I provide a floating lever 90 having a projection 91 at its lower end shown extending into one of the slots 92 provided in the flange 26. Four or eight, or any other desired number of slots may be pro-

vided in the flange 26 in order to provide as many locked positions of the wringer as desired. It is necessary for safety reasons that the clutch mechanism be returned to the neutral position before the swing lock latch is released. If this is not done and particularly if there should be some clothes passing between the rolls of the wringer, the rotation of the drive shaft 28 acting upon the clutch shaft 34 will cause the wringer to swing around the post 24. In order to avoid this dangerous situation, I have provided a substantially rectangular aperture 83 in the upper portion of the floating lever 90. This rectangular aperture is provided with two semi-circular projections 94 and 96 which are adapted to engage a cam projection 98 in the form of a diametric rib provided upon the outer face of the cam member 78.

The floating lever 90 is provided with a slot 101 through which extends a screw 103 into a boss 105 provided upon the lower cylindrical portion 22 of the wringer head 20. A large washer 107 is provided to give a more firm, lateral support for the floating lever 90 in order to keep the upper end in engagement with the cam 98 at all times and to guide the lower end 91 into the slots 92. The floating lever 90 is provided with a knob 109 by which it can be raised to lift it out of one of the slots, such as the slot 92 in the flange 26, in order to release the latching connection between the wringer head and wringer support. If the clutch mechanism should be turned to either the forward or reverse driving arrangements the cam 98 will be in either one of the angular positions illustrated by the dot and dash outline in Fig. 2. Under such circumstances, either the projection 94 or the projection 96 will engage the upper portion of the cam 98 and move the clutch mechanism to the neutral position. It is very desirable that the clutch mechanism operate easily in order to make this interlock arrangement work without too much effort.

A spring 111 having a loop extending around the spacer member 113 and having two end portions 115 and 117 wrapped around the spacer from the clutch operating shaft 83 may be provided to yieldingly urge the floating lever 90 downwardly into its latching position. While the floating lever 90 serves as a swing lock latch and release mechanism as well as an interlock link mechanism, it also serves as an instinctive release mechanism. For this purpose the lower end 91 of the floating lever 90 which projects into the slots in the flange 26 is rounded so that it may pivot in the slots. The slot 101 allows the lever 90 to pivot along the screw 103 as well as to move upwardly with respect to the screw 103, thereby providing a foundation for its naming of floating lever.

When the floating lever 90 is in one of its latching positions any rotational movement of the wringer head 20 upon the wringer support 24, 26 will cause the floating lever 90 to pivot upon the screw 103. This pivoting will be resisted by the upper arms 119 and 121 of the spring 111 which engage opposite sides of the bent-out projection 123 provided in the upper end of the floating lever 90. The upper ends of these arms 119 and 121 are bent so as to have a downward component upon the projection 123 to resiliently urge the floating lever projection 91 downwardly into the slots 92 in the flange 26. They also have a horizontal component tending to hold the floating lever 90 in its central position.

If a force is applied to the wringer tending to turn it in clockwise direction, looking downwardly, the pivot screw 103 will be moved relative to the slot 92 so that the lever 90 will be pivoted (as illustrated by the dot and dash outline) in a counter-clockwise direction as viewed in Fig. 2; thereby bending the arm 119 in a counter-clockwise direction against the tension of the coiled portion 115 of the spring 111. If the clutch mechanism is in either one of the driving positions, the cam 98 will be in either one of the angular positions illustrated by dot and dash lines in Fig. 2. A sufficient movement of the wringer and the lever 90 in this counter-clockwise direction will cause the engagement of the right side of the aperture 93 with the upper or lower end of the cam 98 and a further movement will cause the cam 98 to be cammed to its vertical position thereby moving the clutch mechanism to its neutral position. Similarly, if the wringer is moved in a counter-clockwise direction about the wringer support, the lever 90 will be pivoted in a clockwise direction about the screw 103 against the tension of the spring arm 121. If the cam 98 is in either of its angular positions, a sufficient movement of the lever 90 will cause the left side of the aperture 93 to engage the upper or lower end of the cam 98 and to cam it to the vertical or neutral position.

The torque exerted by the drive shaft 28 upon the wringer head affects this mechanism. If the spring arms 119 and 121 are made of equal tension, then it will be more difficult to push the wringer in the direction opposite the direction of rotation of the drive shaft 28. Assuming that the drive shaft 28 is rotated in the clockwise direction, looking downwardly, then it will be easier to push the wringer in the clockwise direction. The torque applied by the drive shaft 28 will be in direct proportion to the load upon the wringer. In order to compensate for this so that the amount of force required in either direction will be substantially the same, the arm 119 which opposes the clockwise movement of the wringer about the wringer support is provided with a somewhat greater tension. This is done by making the natural unstressed position of the arm 119, substantially as shown in Fig. 4; that is, a greater distance from its normal operating position so that it will be stressed a greater amount when moved to its normal operating position than the arm 121. Thus, in case of an accident a sufficiently powerful push or pull on the wringer or a sufficient tug upon the clothes being fed into the wringer will stop the wringer.

This arrangement has a further safety feature. If a larger wad of clothes than the wringer can handle is fed to the rollers, the torque reaction of the drive shaft 28 upon the wringer head 20 will be sufficient to overcome the tension of the spring 119 to cause the lever 90 to cam the cam 98 to the neutral position. In this way, tearing and undue pulling of the clothes as well as strains upon the mechanism will be prevented. Thus, by this arrangement, the instinctive release mechanism is also made to serve as an overload release mechanism.

While the form of embodiment of the invention as herein disclosed constitutes a preferred form it is to be understood that other forms might be adopted, as may come within the scope of the claims which follow.

What is claimed is as follows:

1. A wringer comprising a wringer head and framework, rolls mounted in the framework, a substantially vertical drive shaft, a drive mech-

anism located in the wringer head operably connecting said drive shaft and one of the rolls, a control means protruding from the wringer head and provided with an operating handle for moving said drive mechanism into operative and inoperative positions, a bearing support having a vertical axis for supporting said wringer head, and a single lever having at its intermediate portion a pivotal connection with said wringer head and at its lower end a pivotal connection with said bearing support, said single lever also having at its upper end means acting directly upon the control means for operating the control means so as to move the drive mechanism from operative to inoperative position upon predetermined movement of the wringer head, framework and lever.

2. A wringer comprising a wringer head and framework, rolls mounted in the framework, a substantially vertical drive shaft, a drive mechanism located in the wringer head operably connecting said drive shaft and one of the rolls, a control means protruding from the wringer head and provided with an operating handle for moving said drive mechanism into operative and inoperative positions, a bearing support having a vertical axis for supporting said wringer head and a single lever having at its intermediate portion a pivotal connection with said wringer head and at its lower end a pivotal connection with said bearing support, said single lever also having at its upper end means acting directly upon the control means for operating the control means so as to move the drive mechanism from operative to inoperative position upon predetermined movement of the wringer head, framework and lever, and spring means acting directly upon said lever for yieldingly preventing the movement of said single lever in either direction from its normal position.

3. A wringer comprising a wringer head and framework, rolls mounted in the framework, a substantially vertical drive shaft, a drive mechanism located in the wringer head operably connecting said drive shaft and one of the rolls, a control means protruding from the wringer head and provided with an operating handle for moving said drive mechanism into operative and inoperative positions, a bearing support having a vertical axis for supporting said wringer head, and a single lever having floating pivotal connection with said wringer head and a removable pivotal connection with said bearing support for restricting the movement of the wringer head relative to said bearing support, said single lever also having means acting directly upon said control means for operating said control means so as to move said drive mechanism from operative to inoperative position upon predetermined movement of the wringer head, framework and lever, said removable pivotal connection being removable to permit unrestricted rotation of the wringer head and framework upon said bearing support, said lever being provided with means effective upon the removal of said pivotal connection for operating said control means to move the drive mechanism to the inoperative position.

4. A wringer comprising a wringer head and framework, rolls mounted in the framework, a substantially vertical drive shaft, a drive mechanism located in the wringer head operably connecting said drive shaft and one of the rolls, a control means protruding from the wringer head and provided with an operating handle for moving said drive mechanism into operative and inoperative positions, a bearing support having a

vertical axis for supporting said wringer head, and a single lever having floating pivotal connection with said wringer head and a removable pivotal connection with said bearing support for restricting the movement of the wringer head relative to said bearing support, said single lever also having means acting directly upon said control means for operating said control means so as to move said drive mechanism from operative to inoperative position upon predetermined movement of the wringer head, framework and lever, and an operating handle for disconnecting said removable pivotal connection to permit unrestricted rotation of the wringer head and framework upon said bearing support.

5. A wringer comprising a bearing support having a vertical axis, a wringer head and framework mounted upon said bearing support, rolls mounted in said framework, a drive mechanism in said wringer head connected to one of said rolls, a control means including a horizontal operating shaft and an operating handle protruding from said head for moving the drive mechanism to and from operative and inoperative position, a vertical lever having a pivotal connection with said wringer head, the lower end of said lever being provided with a pivotal connection with said bearing support, the upper end of said lever and said control means being provided with cooperating means effective upon pivotal movement of the lever for moving said control means to move the drive mechanism from operative to inoperative position.

6. A wringer comprising a bearing support having a vertical axis, a wringer head and framework mounted upon said bearing support, rolls mounted in said framework, a drive mechanism in said wringer head connected to one of said rolls, a control means including a horizontal operating shaft and an operating handle protruding from said head for moving the drive mechanism to and from operative and inoperative position, a vertical lever having a floating pivotal connection with said wringer head, the lower end of said lever being provided with a tongue and slot connection with said bearing support, the upper end of said lever and said control means being provided with cooperating means for moving said drive mechanism to the inoperative position, and a handle for disengaging the tongue and slot connection to disengage said lever from said support.

7. In combination, a clutch mechanism including a rotatable shaft provided with a slidably clutch collar, a control shaft means having its

axis transverse to the axis of said rotatable shaft, a lever having its pivot at one side of the control shaft, said lever being provided with a means for moving and controlling the location of said clutch collar, said control shaft means having an eccentrically located connection with said lever remote from its pivot, and a resilient latching means including a first cooperating portion provided upon said lever beyond said connection and a second cooperating portion cooperating with the first portion to resiliently hold the lever and the clutch collar in a predetermined position.

8. A wringer comprising a wringer head and framework, rolls mounted in the framework, a substantially vertical drive shaft, a drive mechanism located in the wringer head operably connecting said drive shaft and one of the rolls, a control means protruding from the wringer head and provided with an operating handle for moving said drive mechanism into operative and inoperative positions, a bearing support having a vertical axis for supporting said wringer head, and a single lever having at an intermediate portion a pivotal connection with the wringer head, the lower portion of said lever and said bearing support having coacting means for imparting a pivotal movement of the lever upon rotational movement of the wringer head upon the bearing support, the upper portion of said lever and said control means having coacting means for operating the control means so as to move the drive mechanism from an operative position to the inoperative position upon predetermined pivotal movement of the lever.
